UNITED STATES PATENT OFFICE.

LEE W. V. WILMS, OF CHICAGO, ILLINOIS, ASSIGNOR TO THE SCHOLL MANUFACTURING COMPANY, OF CHICAGO, ILLINOIS, A CORPORATION OF NEW YORK.

FELT-SKIVING MACHINE.

1,204,922.

Specification of Letters Patent.

Patented Nov. 14, 1916.

Application filed February 17, 1916. Serial No. 78,903.

To all whom it may concern:

Be it known that I, LEE W. V. WILMS, a citizen of the United States, residing at Chicago, in the county of Cook and State 5 of Illinois, have invented certain new and useful Improvements in Felt-Skiving Machines, of which the following is a specification.

My invention relates to improvements in 10 felt skiving machines, and, in some of its features, more particularly to an improved machine for practising the method of felt skiving disclosed in the patent to David W. Anderson, No. 1,145,654 dated July 6th, 15 1915.

One of the objects of my invention is to provide a simple and efficient mechanism for skiving felt pads or the like that will sever a predetermined portion of the stock 20 without "feathering" the cut edges and that will with certainty produce a smooth, uniform cut-surface.

Another object is to provide simple and 25 advantageous means for positioning and operating the cutting instrumentality; a further object is to provide efficient and desirable mechanism for facilitating rapid changes of the die members to vary the patterns of the articles produced from the felt 30 stock; and other and further objects of my invention will become apparent to those skilled in the art from the following description taken in conjunction with the accompanying drawings, wherein—

Figure 1 is a side elevation of a machine embodying my invention; Fig. 2 is a plan view thereof; Fig. 3 is an enlarged section on line 3—3 of Fig. 1. Fig. 4 is an enlarged section on line 4—4 of Fig. 1. Figs. 5 and 6 40 are diagrammatic views illustrating the cutting action, and Figs. 7 and 8 are views illustrating the result of the cutting action upon the stock and in one finished product.

Referring to the specific embodiment of 45 my invention herein shown, which may, however, be varied in many particulars without departure from the spirit of my invention, the machine is arranged to operate upon a felt sheet A, as a convenient form of stock, the stock, as shown in Fig. 1, being conveniently passed through the large receiving space afforded between a bed frame 10 and a rigid overhanging head frame 11 mounted thereon. In the machine as herein 50 shown the felt will be manipulated by hand

to bring successively the desired portions thereof to position to be operated upon by the coöperating male die structure 12 and female die structure 13. These two die elements provide respectively a reciprocating 60 plunger 14 having a die head 15 convexly shaped for definition of the desired elevation contours of the article to be formed, and a die-plate having an aperture 16 of the plan configuration to be given to the 65 article, the head 15, of course being properly correlated to the contour of the female die opening 16. When the male die structure 12 is suitably elevated, its head 15 forces through the appropriate aperture in the 70 female die element 13 a tensioned or taut node of the felt stock, as illustrated at a in Fig. 5, and by the action of a suitable severing instrumentality 17, the node is scalped at the level of the female die; that is to say 75 the extruded portion of the felt is cut away and permitted elastically to resume its original untensioned state and in so doing to take a convexed form as suggested at a' in Fig. 8, leaving in the felt stock a corresponding recess as indicated at a² in Fig. 7. This method of skiving thus far described, is disclosed in said patent to Anderson above mentioned.

In the advantageous construction, herein 80 shown, of the instrumentalities above generally referred to, I mount the plunger 14 to reciprocate, while held against rotary motion, in a bearing bracket 20 bushed as at 85 21, rotation being prevented by the well 90 known feather - and - slot connection. The vertical throw of the plunger is adjustably limited by arrangement of the stop nuts 22 on the threaded portion 23 of the plunger 95 for stopping abutment against the lower 95 end of the bracket 20. The upper end of the plunger 14 has a head-table 24 on which the demountable die head 15 may be mounted, and retained against lateral displacement by engagement of a stud 25 in a suitable recess in the die head 15. Vertical reciprocating motion, under control of the operator, may be imparted to the plunger by operation of the foot treadle 26 working 100 against the spring 27 to actuate a lever 28 pivoted on a suitable bearing member 28' and working against the anti-friction roller 29 mounted on the extremity of the plunger.

The female die structure 15 preferably 105 comprises a rotatable plate 30, pivoted on a 110

counter-sunk pivot 31 for rotation to bring any one of its numerous, differently-shaped die apertures 16, 16^a, etc., into vertical register with the plunger. Of course for each 5 aperture one or more appropriate male-die-heads 15 will be provided. A spring latch 32 mounted on the lower arm 11^a of the head frame 11 engages such appropriate peripheral notch 33 in the rotatable die plate as to 10 hold the plate securely in desired position.

With respect to the cutting operation I have discovered that in scalping the tensioned nodes the cutting instrumentality performs its function most advantageously 15 if, during its bodily progression through the material, it is given a sawing or draw-cutting motion that is periodically reversed, rather than unidirectionally maintained. For mere verbal distinction I will herein- 20 after refer to the relatively slow and extensive bodily advancement and retraction of the cutting implement as its "reciprocation" and to its relatively short, rapid, periodically-reversing movements transverse to 25 the direction of "reciprocation" as its "vibration." By "vibrating" the cutter blade during the cutting course of its "reciprocation" the tendency of the blade to deflect the felt fibers in either direction transversely 30 to the line of reciprocating progress is not maintained uninterruptedly long enough to result in any detrimental pulling of the node sidewise or in any material shredding of the fibers at the cut edges into a "feather edge," and I find that by thus vibrating the 35 blade during the intervals while it is effecting its cutting advance, no detrimental distortion of the severed pad occurs, no appreciable feather-edging or shredding of the 40 severed edges takes place, very thin articles may be cut with great nicety and the cut surface (which elastically takes a curvature in the completed article) is smooth and free from undulations or "crimps."

45 In the particular construction shown for effecting the desired movements of the cutter the upper and lower arms 11^a and 11^b of the head frame 11 are provided with guide rails 35—35 upon which there slides 50 a reciprocating carrier-frame 36, carrying an electric motor 37 together with the cutting instrumentality and appropriate gearing means. As the motor 37 runs, its pulley 38, belted as at 39, to an elongated pulley 55 40, drives the latter, which is secured to a longitudinal shaft 41 mounted in bearings on the frame arm 11^b and provided with a pulley 42 that drives, through belt 43, a 60 larger gear reducing pulley 44 mounted on a shaft 44' at the head-frame end, and at each end of shaft 44' is a disk 45 bearing a wrist pin 45' connected by a pitman 46 to a pivot pin 47 on the reciprocating carrier frame 36. Consequently, the operation of 65 the motor 37 causes predetermined recipro-

cation of its own carrier frame, which also carries the cutting instrumentality 17. Specifically, the frame 36 has an extension 48 on which there is pivoted as at 49 a transversely vibratable lever 50. The front end 70 of this lever provides a downwardly bent yoke 51, between the ends of which there is horizontally pivotally mounted, as at 52, a cutting blade 53 which preferably has its cutting edge struck on an arc centered at 75 about the pivotal axis of lever vibration. The blade has a heel projection 54 connected by a contractile spring 55 with the yoke 51 and the arrangement is preferably such that when, by the effect of spring 55, the cutting 80 edge of the blade 53 is depressed lightly into contact with the surface of the plate 30, the under surface of said blade stands at a small acute angle to the surface of the plate. Of course the blade bodily reciprocates with 85 the sliding frame 36, and from the motor 37 rapid vibrating motion is imparted thereto, said motor 37 having a pulley 38' from which a belt 39' running over suitable idlers 56 passes around a pulley 57 mounted on the 90 frame extension 48, said pulley 57 having pivoted thereto at 58 a slide block 59 that engages in a slot 60 formed in the rear end of the vibratable lever 50.

In the operation of the machine the attendant positions a piece of stock as shown in Fig. 1, and elevates the plunger to force a node of tensioned material through the female die opening 16 in the plate 30, and then, starting the motor 37, he sets the cutting mechanism in operation. The motor, driving its own reciprocable carrier frame through the belt connection to shaft 41 and pulley 44 as described, advances the knife 105 53 bodily with the cutting edge of the knife sliding over the flat surface of the plate 30, the knife in its forward progress receiving a transverse vibration from the motor through the operative connection of the rear end of lever 50 with the crank member or 110 motor driven wheel 57, and consequently the node is scalped by the reciprocating and vibrating action of the knife, with beneficial results some of which have heretofore been referred to. As soon as the knife has completed its cut and the retraction of the motor frame begins, the attendant drops the plunger 14 by releasing his foot lever 26, manually shifts the stock to locate a fresh portion thereof above the male die 15, and again elevates the plunger, after which, in due course, the cycle of actions above described will be repeated.

While I have herein described in some detail a particular embodiment of my invention that I have found in practice to be advantageous and desirable in many of its details, and certain details of which I may claim for their advantage, it will be understood that in the broader aspects of my in- 125 130

vention, many changes may be made in the specific construction without departure from the spirit of my invention and within the scope of the appended claims.

5 Having described my invention, what I claim is:—

1. In a machine of the character described, the combination of means for presenting a node of elastic material, means for scalping said node comprising a knife mounted for reciprocation and vibration, means to reciprocate said knife, and means to vibrate it during its reciprocation.
2. In a machine of the character described, 15 the combination of means for presenting a tense node of elastic stock, and means for scalping the node comprising a knife mounted for reciprocation and vibration, a motor movable with said knife and connected 20 thereto to vibrate the same, and means for reciprocating said knife and motor.
3. In a machine of the character described, the combination of means for presenting a tense node of elastic stock, and means for 25 scalping the node comprising a knife mounted for reciprocation and vibration, a motor movable with said knife and connected thereto to vibrate the same, and means driven by the motor for reciprocating said 30 knife and motor.
4. In a machine of the character described, the combination of means for presenting a node of elastic fibrous material, and means for scalping said node comprising a knife, 35 motor means for vibrating said knife, and means for reciprocating said knife.
5. In a machine of the character described, the combination of means for presenting a node of elastic fibrous material, and means for 40 scalping said node comprising a knife, a lever carrying said knife, motor means for vibrating said lever, and means for reciprocating said lever.
6. In a machine of the character described, 45 the combination of means for presenting a node of elastic fibrous material, and means for scalping said node comprising a knife, a lever carrying said knife, motor means for vibrating said lever, and means operated by said motor for reciprocating said lever.
7. In a machine of the character described, 50 the combination of means for presenting a node of material, said means including a female die plate, and means for scalping the node comprising a knife, a pivotal support for said knife permitting its cutting edge to travel guidedly upon the die plate, and means for vibrating and reciprocating said knife.

8. In a machine of the character described, the combination of a female die plate, a coöperating male die, mutually arranged for the presentation of a tense node of work through and above the die plate, a vibratable lever having a yoke, a knife pivoted in said yoke, a spring maintaining said knife in position with its cutting edge guided on the die plate and means for vibrating and reciprocating said lever.

9. In a machine of the character described, the combination of a bed frame, a male die member mounted for reciprocation therein, a head frame overhanging the bed frame and providing a pair of guide arms, a die plate having an opening therein carried by said head frame in coöperative relation with the male die, a slide frame in said head frame, a cutting instrumentality carried by said slide frame, a motor carried by said slide frame, and means driven by said motor for reciprocating said slide frame.

10. In a machine of the character described, the combination of a bed frame, a male die member mounted for reciprocation 85 therein, a head frame overhanging the bed frame and providing a pair of guide arms, a die plate having an opening therein carried by said head frame in coöperative relation with the male die, a slide frame in said 90 head frame, a cutting instrumentality carried by said slide frame, a motor carried by said slide frame, and means driven by said motor for reciprocating said slide frame and vibrating said cutting instrumentality.

11. In a machine of the character described, the combination of a plunger, means thereon removably to support a male die head, a rotatable female die member thereabove provided with different die apertures 100 to accommodate different die heads, a node-scalping cutter above said die plate, and means for operating said cutter.

12. In a machine of the character described, the combination of a plunger, means 105 thereon removably to support a male die head, a rotatable female die member thereabove provided with different die apertures to accommodate different die heads, latching means for retaining said plate in different positions, a node scalping cutter above said die plate, and means for operating said cutter.

In testimony whereof I hereunto set my hand in the presence of two subscribing witnesses.

LEE W. V. WILMS.

In the presence of—

RALPH W. LINTON,
M. FOSTER.
